(57) **CLAIM**

The ornamental design for a golf tee base, as shown and described.

DESCRIPTION

FIG. 1 is a top-front-left perspective view of a golf tee base showing my new design;

FIG. 2 is a bottom-rear-right perspective view thereof;

FIG. 3 is a front elevated view thereof;

FIG. 4 is a rear elevated view thereof;

FIG. 5 is a top plan view thereof;

FIG. 6 is a bottom plan view thereof;

FIG. 7 is a right elevated view thereof;

FIG. 8 is a left elevated view thereof;

FIG. 9 is a top perspective view thereof, showing the golf tee base connected to a tee body; and,

FIG. 10 is a bottom perspective view thereof, showing the golf tee base connected to the tee body.

The broken-line showing of a tee body in FIGS. 9 and 10 are included for the purpose of showing environmental structure and form no part of the claimed design.
